No. 37,025.

Patented July 5, 1904.

UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A BREAD-TRAY.

SPECIFICATION forming part of Design No. 37,025, dated July 5, 1904.

Application filed June 3, 1904. Serial No. 211,028. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for Bread-Trays, of which the following is a specification, reference being had to the accompanying drawings, forming part thereof.

10 In the accompanying drawing the figure

shows a plan of a bread-tray, showing my new design.

What I claim as new, and desire to secure by Letters Patent, is—

The ornamental design for a bread-tray, as 15 herein shown.

ALBERT STEFFIN.
